CIRCUIT INTERRUPTING DEVICE

Earl F. Beach, Penn Township, Allegheny County, Pa., assignor to Westinghouse Electric Corporation, East Pittsburgh, Pa., a corporation of Pennsylvania

Application October 4, 1954, Serial No. 460,170

11 Claims. (Cl. 200—146)

This invention relates to circuit interrupting devices in general, and, more particularly, to disconnecting switches with particular relation to disconnecting switches that are adapted to be opened under load conditions.

In many instances it is desirable to open a high voltage disconnecting switch while load current is flowing in the circuit in which it is connected. For example, in many installations, high voltage transformers are constantly connected to the high voltage line and infrequently require servicing. It is then necessary to disconnect such a high voltage transformer from the high voltage circuit, and during such disconnecting operation it is necessary to interrupt the magnetizing current flowing from the high voltage line into the high voltage transformer.

If this magnetizing current were drawn between the blade-shaped contact and the stationary jaw contact of a conventional disconnecting switch the contact surfaces would become pitted or eroded so that following only a few such operations the contact surfaces would not be suitable for carrying the full load current. Thus the switch members would become burned or fused because of the heat of the arc depending upon the amount of current in the circuit at the particular instant that the switch is opened.

There is also the possibility, under more severe circuit conditions, that a long arc may be sustained and establish itself between the switch and an adjacent circuit or ground when the attempt is made to interrupt the load current by a conventional disconnecting switch. It is a general purpose of my invention to provide an improved load-break disconnecting switch which will interrupt the load current interiorly within an arc interrupting structure and not exteriorly thereof at the open switch contacts.

A further object of my invention is to provide an improved and highly efficient load-break disconnecting switch in which the contact structure of the arc-extinguishing device is opened and closed by snap action.

Still a further object of my invention is to provide an improved operating mechanism for the arc-interrupting device of a load-break disconnecting switch.

Yet another object is to provide a load-break disconnecting switch in which the circuit is broken within the arc-interrupting device, and, during the closing operation, the circuit is made between the contacts of the arc-interrupting device and not at the switch contact members.

It will be apparent to those skilled in the art that certain features of my invention are applicable to switches of both the indoor and outdoor type. Merely for purposes of illustration do I disclose my invention as applied to a load-break disconnecting switch of the indoor type, which is preferably mounted in a cubicle construction.

Further objects and advantages will readily become apparent upon reading the following specification taken in conjunction with the drawings, in which:

Figure 1 is a side elevational view of a load-break dis-

2

connecting switch embodying features of my invention, and shown in the closed-circuit condition;

Fig. 2 is a plan view, partially in section, of a portion of a three-phase installation mounted in a suitable cubicle and showing how the three phases may be simultaneously opened by a single common drive shaft;

Fig. 3 is an enlarged plan view, partially in section, of my improved load-break disconnecting switch, the several parts thereof being indicated in the closed-circuit position;

Fig. 4 is a fragmentary vertical sectional view through the interrupting device and mechanism of my invention;

Fig. 5 is a vertical sectional view taken substantially along the line V—V of Fig. 4, the several parts thereof being indicated in the closed circuit position;

Fig. 6 is a side elevational view, partially in section, of the hinge base of my improved disconnecting switch;

Fig. 7 is a fragmentary side elevational view, partially in section, of the load-break disconnecting switch of my invention in the partially open-circuit position, with the over-center spring mechanism being shown in its toggle position; and

Fig. 8 is a fragmentary sectional view through the mechanism housing, indicating the position of the several parts in the fully open-circuit position of the interrupting device, the several parts being drawn to a reduced scale.

Referring to the drawings, and more particularly to Figs. 1 and 2 thereof, the reference numeral 1 designates a cubicle, preferably fabricated of sheet metal and enclosing a plurality of interrupting devices 2, only one of which is shown, controlling a three-phase circuit. By means of a drive shaft 3, extending through a bearing structure 4, and externally actuated by a crank arm 5, connected by a link 6 to a suitable drive mechanism, the three interrupting devices 2 may be simultaneously actuated to open and close the three-phase circuit.

The drive shaft 3 has clamped thereto a plurality of crank arms 7, preferably one for each interrupting device 2; and the outer end of each crank arm end 7 is connected by an insulating link 8 to a lug 9 disposed at the upper end of each hinge mechanism housing or frame 10, as more clearly indicated in Figs. 4 and 7 of the drawings.

Thus actuation of the crank arm 5, by any suitable mechanism, will effect rotation of the drive shaft 3 and hence a simultaneous opening movement of the three insulated links 8 to effect an opening or a closing operation of the three interrupting devices 2, as indicated by the full and dotted lines of Fig. 1.

Referring more particularly to Fig. 1 it will be observed that there is provided a channel base 12, which supports a pair of insulator columns 13, 14. The insulator column 13 serves to fixedly support a terminal or hinge base 15, more particularly shown in Figs. 5 and 6 of the drawings. The hinge base 15 is bolted by bolts 16 to the upper cap 17 of the insulator column 13. The hinge base 15 serves not only to pivotally support the hinge mechanism housing 10, but also to provide a terminal pad 18 for an external line connection, as is well understood by those skilled in the art.

The other insulator column 14, supported upon the base 12, is utilized to fixedly support a main contact 20, an elongated stationary auxiliary contact 21 and a second terminal pad 22, to which the other line connection may be made to the interrupting device 2. The main contact 20 cooperates with a main switch arm or rotatable bridging contact assembly, generally designated by the reference numeral 23, and comprising a pair of cooperating contact blades 24, as more clearly indicated in Figs. 2 and 3 of the drawings. The contact blades 24 are spaced apart by a channel-shaped member 25 bolted thereto, as at 26, and their right-hand ends, as viewed in Fig. 3,

are supported on the hinge pins 27, and secured by bolts 28 to the sides 29 of the hinge mechanism housing 10.

A metallic sleeve support 30 is secured by bolts 31 to the left-hand end of the frame 10, as shown in Fig. 4 of the drawings. The support 30 has an internally threaded recess 32, into which is threadedly secured the end of an insulating interrupting tube 33, as shown in Fig. 4. The base of the recess 32 is apertured, as at 34, to accommodate therethrough a movable arcing contact rod 35, which is biased toward the open position by a compression spring 36. The compression spring 36 seats at one end upon the end washer 37 of a stack of washers, which collectively define an interrupting arc passage 38, through which the movable arcing contact rod 35 moves during the opening operation.

The other end of the accelerating compression spring 36 seats against a washer 39 bearing against a sleeve 40, which is fixedly secured to and movable with the contact rod 35, as indicated in Fig. 4 of the drawings.

Preferably, disposed internally within the interrupting tube 33 between the washers 37 and the sleeve support 30 is a spacing tube 41. A relatively stationary arcing contact 42 is secured by a threaded connection to a perforated end cap 43, the latter being threadedly secured, as at 44, to an internally threaded outer end 45 of the interrupter tube 33. The perforations or apertures 46, provided in the end cap 43, permit gases, evolved during the interrupting operation within the interrupting tube 33, to flow thereout to atmosphere.

The outer end of the stationary arcing contact 42 is extended to provide a movable auxiliary contact 47, which bears against the side of the auxiliary contact 21, as indicated in Fig. 1 of the drawings. The right-hand end of the movable arcing contact rod 35 is enlarged, as shown in Fig. 3, to form a movable contact yoke 48, having a bearing aperture 49 therethrough to accommodate a pin 50. Encircling the pin 50 are a pair of guide rollers 51 which are guided in slots, or race tracks 52 integrally formed with the mechanism housing 10, as more clearly shown in Fig. 5 of the drawings. Also encircling the pin 50 is a pair of shoulder bushings 53, which move in slots 54 provided in the sides or furcations 55 of a U-shaped operating lever 56, the configuration of which is more clearly apparent from an inspection of Fig. 5 of the drawings. The lower ends of the furcations 55 are perforated, as at 57 (Fig. 5) to accommodate hinge pins 58 welded to the inner sides of the mechanism housing 10.

The hinge base 15 forms a pair of upstanding supports 59, having apertures 60 internally threaded to threadedly secure into place the hinge pins 27, as shown in Fig. 5. Also the hinge base 15 has an apertured lug 61, through which extends a pin 62. The pin 62 pivotally supports a spring end 63 having grooves 64 onto which is threaded one end of a helical tension spring 65. The upper end of the tension spring 65 threads in a similar manner onto a spring support 66, the latter being apertured to receive a pin 67, the ends of which are journaled in apertures provided in the furcations 55 of the U-shaped operating lever 56. Preferably spacing sleeves 68 encircle the pin 67 to maintain the upper spring support 66 in a central position, as shown in Fig. 5.

In the closed-circuit position of the interrupting device 2, the current passes from the terminal pad 22 through the contact 20 and hence through the main switch arm 23 to the metallic supports 59 and thence to the other terminal pad 18 of the hinge base 15. Another parallel path is provided by the auxiliary contact 21, the movable auxiliary contact 47, the stationary arcing contact 42, the movable arcing contact rod 35 to the contact yoke 48. A flexible connector 69 transmits the current from the contact yoke 48 to the rotatable housing 19, and then through the hinge pins 27 to the metallic supports

59 of the hinge base 15, and thence to the other terminal pad 18.

It will be obvious that the second parallel path for current flow has a greater resistance than the first-mentioned current path, and consequently in the closed circuit position of the device practically all of the current will flow through the device by way of the main contact 20 and the main switch arm 23.

In the closed position of the switch (Fig. 4) the line 10 of action of the tension spring 65 is to the left of the pivot 58 for the link 56 and biases it in counterclockwise direction so as to tend to move the arcing contact rod to the left and into pressure engagement with the stationary arcing contact 42.

15 When it is desired to open the interrupting device 2, the drive shaft 3 is rotated, which effects through the insulating link 8 clockwise rotation of the mechanism housing 10 about the hinge pins 27. This will bring the hinge pins 58 and the pin 67 into line with the pin 62 so that the tensile stress exerted by the tension spring 65 will be exerted directly axially of the U-shaped operating lever 56 in a manner more clearly illustrated in Fig. 7 of the drawings. In this position the overcenter spring mechanism 70 is in toggle on dead center, and there is 25 no force exerted by the spring 65 to effect opening or closing motion of the contact rod 35. As shown in Fig. 7, at this time the main switch arm 23 has separated from the main contact 20 to provide a gap therebetween, as indicated by the distance "D" of Fig. 1. During this 30 time, however, the auxiliary contacts 21, 47 have maintained contact so that the circuit through the interrupting device 2 extends therethrough by way of the auxiliary interrupting device 71, including the stationary and movable arcing contacts 42, 35.

35 Further clockwise rotation of the mechanism housing 10 about the hinge pins 27, as effected by continued rotation of the drive shaft 3, causes movement of the hinge pins 58 to the left of a straight line drawn between pins 62 and 67, so that the line of action of the spring force, 40 exerted by tension spring 65 is to the right of pins 58. This effects snap-opening movement of the contact rod 35 at approximately the position "A" of Fig. 1, the guide rollers 51 guiding the motion of the contact rod 35 in a substantially straight-line motion.

45 The insulating washers 37 defining the arcing passage 28 are preferably of a suitable gas-evolving material, such as fiber, boric acid, or like materials, so that upon separation of the stationary and movable arcing contacts 42, 35, the arc established therebetween will be drawn within arcing passage 38 to effect evolution of considerable gas therein. This gas blast will flow axially of the established arc, and outwardly from the arc passage 38 through the apertures 46 provided in the perforated end cap 43. Current interruption will quickly be brought 50 about, and continued clockwise rotation of the mechanism housing 10 to the position "B" of Fig. 1 will effect an adequate isolating gap in the circuit between the auxiliary contacts 21 and 47 in the fully open circuit position of the interrupting device 2, the several parts of the over-center spring mechanism 70 then having a disposition such as viewed in Fig. 8 of the drawings with the line of action of the spring lying to the right of the pivot 58 and biasing the contact rod 35 to open position.

55 During the closing operation the events transpire in a reversed sequence, namely the drive shaft effects counterclockwise rotative motion of the mechanism housing 10 about the hinge pins 27 thereby bringing the location of the pins 58 closer to a straight line drawn between the pins 62, 67. At about 25 angular degrees from the closed 60 position the several parts of the mechanism 70 are substantially in toggle. Further, counterclockwise rotation of the mechanism housing 10 will bring the line of action of the tension spring 65 to the left of the pins 58, and the over-center spring 65 will effect snap-closing of the 65 movable arcing contact rod 35 into engagement with the

relatively stationary arcing contact 42. Since at this time the auxiliary contacts 21 and 47 are in engagement, the circuit will be completed through the device by way of the auxiliary interrupter 71. Final closing rotative motion of the mechanism housing 10 effects closing contacting engagement between the main contact 20 and the main switch arm 23. Since, as mentioned, the resistance through the contacts 20, 23 is considerably less than that by way of the auxiliary interrupter 71, the current will be transferred to the lower resistance path between the contacts 20 and 23.

From the foregoing description of my improved interrupting device it will be apparent that I have provided snap-opening and snap-closing motion of the movable contact rod 35. It will also be observed that the circuit is made and is broken during respective closing and opening operations by way of the interrupting device 71, and not at the main contact 20. The tension spring 65 provides a high speed of motion for the movable contact rod 35, and the construction of the over-center spring mechanism 70 is such that slight rotative movement of the drive shaft 3 effects a considerable change in the line of action exerted by the tension spring 65. This is very important in conserving floor space and in utilizing only slight rotative motion of the drive shaft 3.

It will be observed that at the time of the breaking of the circuit within the interrupting device 71 the contact 20 and the end of the main switch arm 23 are so far separated at this time that there is no chance of external breakdown or flashover between these points upon interruption of the circuit within the interrupting device 71. In the "B" position of Fig. 1, which represents approximately 70° of rotative travel, it will be noted that a considerable disconnecting gap is provided between parts at opposite potential.

Although I have shown and described a specific structure, it is to be clearly understood that the same was merely for the purpose of illustration, and that changes and modifications may readily be made therein by those skilled in the art without departing from the spirit and scope thereof of the invention.

I claim as my invention:

1. A circuit interrupting device including spaced terminals, a rotatable bridging contact assembly supported for rotation around an axis on one terminal and adapted to be swung around said axis into contacting bridging engagement with the other spaced terminal to complete the circuit between the terminals, an auxiliary interrupting device having a movable auxiliary contact, an operating lever pivotally supported on a movable part of the contact assembly at a point off of said axis which rotates during the opening and closing operations, means positively connecting one end of the operating lever at all times with the movable auxiliary contact, and means biasing the operating lever to one side or the other of the axis of its pivotal support.

2. A circuit interrupting device including spaced terminals, a rotatable bridging contact assembly supported for rotation around an axis on one terminal and adapted to be swung around said axis into contacting bridging engagement with the other spaced terminal to complete the circuit between the terminals, an auxiliary interrupting device having a movable auxiliary contact, an operating lever pivotally supported on a movable part of the contact assembly at a point off of said axis which rotates during the opening and closing operations, means connecting the operating lever with the movable auxiliary contact, and an over-center biasing spring for biasing the operating lever to one side or the other of the axis of its pivotal support.

3. A circuit interrupting device including spaced terminals, a rotatable bridging contact assembly supported for rotation around an axis on one terminal and adapted to be swung around said axis into contacting bridging engagement with the other spaced terminal to complete the

circuit between the terminals, an auxiliary interrupting device having a movable auxiliary contact, an operating lever pivotally supported on a movable part of the contact assembly at a point off of said axis which rotates during the opening and closing operations, means connecting the operating lever with the movable auxiliary contact, and an over-center tension spring having one end thereof connected to a point intermediate the ends of the operating lever.

10 4. The combination in a load-break switch of a pair of spaced terminals, a rotatable switch arm assembly mounted for rotation around an axis on one terminal, means for swinging said switch arm assembly about said axis so that the free end of the switch arm assembly makes contacting and disconnecting engagement with the other spaced terminal, an arcing horn mounted on said other spaced terminal, an auxiliary interrupting tube extending in generally the same direction as the switch arm assembly and having a protruding arcing horn which makes engagement with the first-mentioned arcing horn at least during a portion of the opening operation, a movable auxiliary contact associated with the auxiliary interrupting tube, an operating lever pivotally supported on a rotatable portion of the switch arm assembly at a point off of said axis, means operatively connecting the operating lever with the movable auxiliary contact, and means biasing the operating lever to one side or the other of the axis of its pivotal support.

15 5. The combination in a load-break switch of a pair of spaced terminals, a rotatable switch arm assembly mounted for rotation around an axis on one terminal, means for swinging said switch arm assembly about said axis so that the free end of the switch arm assembly makes contacting and disconnecting engagement with the other spaced

20 terminal, an arcing horn mounted on said other spaced terminal, an auxiliary interrupting tube extending in generally the same direction as the switch arm assembly and having a protruding arcing horn which makes engagement with the first-mentioned arcing horn at least during a portion of the opening operation, a movable auxiliary contact associated with the auxiliary interrupting tube, an operating lever pivotally supported on a rotatable portion of the switch arm assembly at a point off of said axis, means operatively connecting the operating lever with the movable auxiliary contact, and an over-center biasing spring for biasing the operating lever to one side or the other of the axis of its pivotal support.

25 6. The combination in a load-break switch of a pair of spaced terminals, a rotatable switch arm assembly mounted for rotation around an axis on one terminal, means for swinging said switch arm assembly about said axis so that the free end of the switch arm assembly makes contacting and disconnecting engagement with the other spaced terminal, an arcing horn mounted on said other spaced terminal, an auxiliary interrupting tube extending in generally the same direction as the switch arm assembly and having a protruding arcing horn which makes engagement with the first-mentioned arcing horn at least during a portion of the opening operation, a movable auxiliary contact associated with the auxiliary interrupting tube, an operating lever pivotally supported on a rotatable portion of the switch arm assembly at a point off of said axis, means operatively connecting the operating lever with the movable auxiliary contact, and an over-center tension spring having one end thereof connected to a point intermediate the ends of the operating lever.

30 7. A circuit interrupting device including spaced terminals, a rotatable bridging contact assembly supported for rotation around an axis on one terminal and adapted to be swung around said axis into contacting bridging engagement with the other spaced terminal to complete the circuit between the terminals, an auxiliary interrupting device having a movable auxiliary contact, a U-shaped operating lever pivotally mounted on a rotatable portion 35 of said bridging contact assembly, means interconnecting

the movable auxiliary contact with the U-shaped operating lever adjacent the bight portion thereof, and an over-center spring connected at one end to a portion of the U-shaped operating lever intermediate the ends thereof.

8. The combination in a load-break switch of a pair of spaced terminals, a rotatable switch arm assembly mounted for rotation around an axis on one terminal, means for swinging said switch arm assembly about said axis so that the free end of the switch arm assembly makes contacting and disconnecting engagement with the other spaced terminal, an arcing horn mounted on said other spaced terminal, an auxiliary interrupting tube extending in generally the same direction as the switch arm assembly and having a protruding arcing horn which makes engagement with the first-mentioned arcing horn at least during a portion of the opening operation, a movable auxiliary contact associated with the auxiliary interrupting tube, a U-shaped operating lever pivotally mounted on a rotatable portion of the switch arm assembly at a point off of said axis, means interconnecting the movable auxiliary contact with the U-shaped operating lever adjacent the bight portion thereof, and an over-center spring connected at one end to a portion of the U-shaped operating lever intermediate the ends thereof.

9. A circuit interrupting device including spaced terminals; a rotatable bridging contact assembly including a frame, the frame being pivotally supported about an axis on one terminal so that the bridging contact assembly may be swung rotatively around said one terminal into contacting bridging engagement with the other spaced terminal to complete the circuit between the terminals, the bridging contact assembly including a main contact blade and an auxiliary interrupting tube both mounted on the frame and extending outwardly therefrom substantially parallel to one another, the main blade having a length substantially equal to the spacing distance between the spaced terminals, the auxiliary interrupting tube having an auxiliary contact, said other spaced terminal having an auxiliary contact making engagement with the first said auxiliary contact during the initial portion of the opening operation following disengagement of the main contact blade from said other terminal, and means for establishing an arc within the tube and extinguishing it therein.

10. A circuit interrupting device including spaced ter-

minals, a rotatable bridging contact assembly including a frame, the frame being pivotally supported about an axis on one terminal so that the bridging contact assembly may be swung rotatively around said one terminal into contacting bridging engagement with the other spaced terminal to complete the circuit between the terminals, the bridging contact assembly including a main contact blade and an auxiliary interrupting tube both mounted on the frame and extending outwardly therefrom substantially parallel to one another, the auxiliary interrupting tube having an auxiliary contact, the main blade having a length substantially equal to the spacing distance between the spaced terminals, said other spaced terminal having an auxiliary contact making engagement with the first said auxiliary contact during the initial portion of the opening operation following disengagement of the main contact blade from said other terminal, means for establishing an arc within the tube and extinguishing it therein, and the main contact blade being shorter than the auxiliary interrupting tube.

11. A load-break disconnecting switch including a pair of spaced terminals, relatively stationary insulating supporting means for supporting said pair of spaced terminals a fixed distance apart, a rotatable bridging contact assembly supported for rotation relative to said supporting means around an axis on one terminal, the rotatable bridging contact assembly being adaptable to be swung around said axis into contacting bridging engagement with the other spaced terminal to complete the circuit between the terminals, the bridging contact assembly including a rotatable auxiliary interrupting device having a movable auxiliary contact, an operating lever pivotally supported adjacent one end thereof on a rotatable part of the contact assembly at a point off of said axis which rotates during the opening and closing operations, means connecting said movable auxiliary contact at all times adjacent the other end of the operating lever; and means biasing said operating lever to one side or the other of the axis of its pivotal support.
